(57) CLAIM

The ornamental design for a massage slipper, as shown and described.

DESCRIPTION

FIG. 1 is a front elevational view of a massage slipper showing my new design;

FIG. 2 is a rear elevational view thereof; and

FIG. 3 is a left elevational view thereof;

FIG. 4 is a right side view thereof;

FIG. 5 is a top side view thereof;

FIG. 6 is a bottom plan view thereof;

FIG. 7 is a perspective view of a massage slipper showing my new design;

FIG. 8 is another perspective view thereof; and,

FIG. 9 is a partial enlarged view of FIG. 7.

The broken lines in the figures are for the purposes of illustrating portions of the massage slipper, which form no part of the claimed design.
